AUTOMOBILE HEATER

Albert A. Paley, Kew Gardens, N. Y.

Application October 26, 1953, Serial No. 27,319

Term of patent 14 years

(Cl. D14—6)

Fig. 1 is a side elevational view of an automobile heater embodying my new design;

Fig. 2 is an end elevation, from the left side of Fig. 1;

Fig. 3 is an end elevation, from the right side of Fig. 1.

It is to be noted that the entire periphery of the heater cylinder is covered with perforations of the type shown.

I claim:

The ornamental design for an automobile heater, as shown and described.
